(57) CLAIM

The ornamental design for a “domed cup lid”, as shown and described.

DESCRIPTION

This application is related to commonly owned U.S. Utility patent application Ser. No. 09/618,803 filed concurrently herewith, entitled “domed cup lids especially for use with frozen carbonated beverages”, the entire content of which is expressly incorporated hereinto by reference.

FIG. 1 is a perspective view of a domed cup lid which embodies my new and original design therefor, the dashed line in FIG. 1 showing a cup representing environment only and forms no part of my claimed design;

FIG. 2 is a top plan view of thereof;

FIG. 3 is a side elevational view thereof; and,

FIG. 4 is a bottom plan view thereof.
